UNITED STATES PATENT OFFICE.

ROBERT AMORY, OF BOSTON, MASSACHUSETTS.

INSTRUMENT FOR SEPARATING THE CUTICLE FROM THE NAILS.

No. 902,546.

Specification of Letters Patent.

Patented Nov. 3, 1908.

Application filed January 18, 1908. Serial No. 411,399.

To all whom it may concern:

Be it known that I, ROBERT AMORY, a citizen of the United States, residing at Boston, in the county of Suffolk and State of Massachusetts, have invented new and useful Improvements in Instruments for Separating the Cuticle from the Nails, of which the following is a specification.

This invention relates to an improved instrument for separating the cuticle from the nails. The use of such an instrument for separating the cuticle and flesh from a growing nail, when the instrument is made of metal is likely to cause onychia, whitlow and ingrowing toe-nails, especially when the cuticle or flesh from the soft tissues is attached to the nail and, when this elongates with the growing nail, is pulled away from the surrounding flesh making a fissure, thus exposing the wound to absorbing pus or other deleterious liquid by contact with unclean instruments, materials or articles.

The object of this invention is to obviate this risk to the user and to this end an instrument of wood or other vegetable matter is charred or carbonized at one end thereof to sterilize the wood and is then moistened in water, preferably anti-septic, which will soften the charred substance and prevent the cutting of the cuticle or flesh at the side of the nail or under the separated nail at the ends of fingers, thumbs or toe-nails after the wood or other vegetable matter is charred and the end moistened in water, all the free and superfluous charred material is removed by friction so as to leave the said end smooth and clean.

It is more desirable, convenient and easier of manipulation to use a conical smooth point when separating the cuticle or flesh from the nail, but the conical point is not absolutely essential to the invention herein-after described. It is, however, very essential that the end of the instrument shall be clean and sterilized. Charring or carbonizing of the wood may be done in a variety of ways, either by igniting the same and afterwards moistening or by subjecting the same to the action of acids or other medicaments to produce the charred sterilized point upon the instrument which is to be used.

The invention consists in the instrument hereinafter described and set forth in the claims.

The figure of the drawings illustrates a side elevation of a desirable form of my improved instrument for separating the cuticle from the nails.

In the drawings 1 is a handle of any convenient form having a flange 2 thereon which separates the handle from the stem 3, said stem being recessed to receive the shank 4 of an end piece 5. The end piece 5 is preferably conical in shape and formed of wood or other vegetable material. Said end piece 5 may be made in one piece with the stem 3 and handle 1, but preferably, is made detachable, as shown in the drawing, so that the same handle can be used with a large number of different end pieces, which end pieces may be made of various shapes and sizes to suit the convenience or desire of the user.

The end piece 5 is sterilized before using in the following manner: It is first ignited and allowed to burn until a certain amount of the end piece has become charred and is then plunged into a glass of antiseptic water, whereby the further charring of the wood ceases and the carbonized portion of said wood is moistened. Said carbonized portion of the wood is then rubbed with a cloth to remove the superfluous carbonized material, leaving the end of the wood charred smooth and of a conical form and in condition to be used for the purpose hereinbefore set forth without any danger of cutting or injuring the flesh and without any danger of transferring noxious or suppurating matter from the instrument to the flesh of the person using it and so clean that the same will not soil the fingers or toes of the person using it by reason of any free carbonized matter.

While it is preferable to char the instrument in the manner hereinbefore set forth, I do not confine myself to the charring of the same by ignition, as it is evident that the wooden end piece may be charred by the use of sulfuric or other acid substance and the water which is used to moisten the instrument after the charring operation may be supplied with an alkali to neutralize any ex-

cess of said acid, the resulting instrument being thus partially charred, as in the manner hereinbefore set forth.

Having thus described my invention, what I claim and desire by Letters Patent to secure is:

An instrument for separating the cuticle from the nails consisting of a handle and an end piece formed of wood or other vegetable substance and having a charred end, said end

piece having a stem adapted to fit in a recess provided in said handle.

In testimony whereof I have hereunto set my hand in presence of two subscribing witnesses.

ROBERT AMORY.
